UNITED STATES PATENT OFFICE.

ALVAH L. POWELL, OF MILES CITY, MONTANA, ASSIGNOR TO THE A. L. POWELL POWER COMPANY INCORPORATED.

ENGINE.

Application filed November 9, 1923. Serial No. 673,858.

My invention relates to improvements in internal combustion engines in which I obtain direct rotary motion by means of the inertia of a fluid.

More specifically, my invention relates to improvements in a double-acting internal combustion engine having a plurality of pistons which impart motion to a fluid contained between the pistons, which fluid, by 10 my novel means, imparts rotary motion to a pulley.

Heretofore, it has been customary to connect the piston of an engine to a crank shaft by means of a pitman, but there are many 15 disadvantages to such an arrangement, such as the side slap of the piston against the cylinder wall, the knock and attending noise caused by imperfect connection between the pitman and the crank or the wrist pin, and 20 furthermore, such an arrangement of parts causes the crank to be on dead center at the very moment that the piston starts on the travel of its explosion stroke. I seek to 25 overcome all of these disadvantages by providing a simple and novel means whereby the motion of the piston is converted into a constantly rotating motion of a driven pulley.

Within the pulley, I provide a large central bore closed at one end by means of a 30 suitable valve, and around said bore, I provide a number of small spiral bores, each of which is provided with a valve on the side of the pulley opposite the valve of the 35 large bore. As the fluid is driven by the pistons through the large bore, it impinges against spiral ridges carried by the pulley and rotates the same. As the liquid is driven in the opposite direction through the 40 small spiral bores, the fluid or liquid impinges against the sides of the spirals and rotates the pulley. The object of the valves is to control the direction of flow of the 45 fluid through the bores.

In the accompanying drawings, I show an application of my improvement in which

Figure 1 is a side elevation partly in section of an engine embodying my invention,

Figure 2 is a cross section on the line 2—2 50 of Fig. 1, showing the fluid channels or bores, and

Figure 3 is a sectional view of the check valves used in my improved engine.

A base 1 is provided with two upstanding 55 supports 2, on which supports are rigidly

mounted two cylinders 3 and 4, the axes of said cylinders lying in the same straight line. In each of said cylinder, I provide an air inlet 5, a gas inlet 6 and exhaust 7, the two inlets and exhaust being conventional. In each of the cylinders 3 and 4, I provide cooperating reciprocating pistons 8 and 9 respectively. Suitable means (not shown) are provided to govern the explosions that take place in the two cylinders 3 and 4, which explosions are so timed that when either piston is on its explosion stroke, the other piston is on its exhaust stroke.

The side walls of each of the cylinders 3 and 4 are beveled at their inner ends as indicated by the reference characters 10 and 11. A pulley 13 is interposed between the cylinders 3 and 4, which pulley is provided on each side thereof with a cylindrical flange 12 having its inner or outer periphery beveled so as to make a wedge fit with the beveled edges 10 and 11 of the cylinders 3 and 4. A large straight opening 14 is provided within the pulley 13, which opening extends substantially straight through the said pulley, and which opening is closed at one end thereof by a valve 15 of any conventional construction. A plurality of small openings 16 extend through the pulley, but these openings or channels are spiral in form as clearly shown by dotted lines in Fig. 1. Each of these openings is closed by a valve 17, the valve 15 being on the opposite side of the pulley from the valve 17.

In practice, it is necessary to provide some 90 means whereby the fluid 18 interposed between the cylinders 8 and 9 may be prevented from leaking at the points of contact between the rotating pulley and the stationary cylinders. I successfully prevent such 95 leakage by providing the beveled edges 10 and 11, on the cylinders 3 and 4, contacting with the beveled edges on the flange 12 of the pulley 13. This makes a fluid tight fit 100 when properly adjusted.

Any suitable means may be provided for 105 lubricating the bearings so formed, but as the lubricating feature forms no part of my invention, I have illustrated no particular lubricating means.

I also find it preferable to extend the hub of the pulley 13 so as to occupy the space between the beveled parts 10 and 11 of the cylinders 3 and 4, as is clearly shown in Fig. 1. The object of this construction is 110

to further insure that there shall be no leakage of fluid at the bearings, and also to hold the axis of rotation of the pulley 13 stationary.

I furthermore find it desirable to provide ridges 19 extending spirally of the opening 14. As the piston 8 is forced to the right in Fig. 1, the fluid is forced through the small openings 16, opening the valves 17, and thereby forcing the fluid into the cylinder 4, moving the piston 9 to the right. The momentum of the fluid striking the sides of the openings 16 causes the pulley 13 to be rotated clockwise when viewed from the right-hand side of Fig. 1. The explosion now takes place in the cylinder 4 and the fluid is forced through the opening 14, opening the valve 15 in the cylinder 3, the momentum of the fluid striking against the ridges 19 rotating the pulley 13 clockwise.

Obviously, many modifications might be made in this invention without departing from the spirit and scope thereof. I, therefore, do not wish to limit myself to the specific embodiment herein shown except as I might limit myself in the annexed claims.

I claim:

1. In an engine, a plurality of cylinders, a piston in each of said cylinders, a pulley interposed between the cylinders and provided with a large bore having inwardly extending spiral ridges, said pulley being also provided with a plurality of spiral bores, a valve at one end of the large bore, a valve

at the opposite end of each of the spiral bores and a fluid interposed between said pistons and adapted to pass through the bores.

2. In an engine, a plurality of cylinders, a piston in each of said cylinders, a pulley interposed between the cylinders and provided with a large central bore having inwardly extending spiral ridges, said pulley being also provided with a plurality of spiral bores extending in an opposite direction from the spiral ridges, a valve at the end of the large bore, a valve at the opposite end of each of the spiral bores, and a fluid interposed between said pistons and adapted to pass through the bores.

3. In an engine, a plurality of cylinders, a piston in each of said cylinders, a pulley interposed between the cylinders and provided with a large bore having inwardly extending spiral ridges, said pulley being also provided with a plurality of spiral bores, a valve at one end of the large bore, a valve at the opposite end of each of the spiral bores, a fluid interposed between said pistons, said valves serving as a means to alternately direct the fluid to the large bore and then to the spiral bores, said ridges and spiral bores being of such a configuration that the pulley is rotated in one direction regardless of the direction of movement of the said fluid, actuated by the said pistons.

In testimony whereof I affix my signature.

ALVAH L. POWELL.
